APPARATUS FOR MAKING SINUOUS BENDS
IN LONG WORKPIECESArthur W. Payne, Detroit, Mich., assignor to
Bundy Tubing Company, Detroit, Mich., a cor-
poration of Michigan

Application May 8, 1947, Serial No. 746,706

11 Claims. (Cl. 153—40)

1
This invention relates to an apparatus for forming long work pieces, such as a tube, into coils of serpentine shape having a series of reverse bends.

When an elongated piece of stock, such as a tube, is formed into a serpentine coil by the successive making of reverse bends therein, a problem is immediately encountered in the handling of the work. In some operations some of the stock is required to be swung through the angle of the bend relative to other portions of the stock and since the stock, in its initial form is quite long, it is usually the practice to swing the formed portions of the coil relative to the straight run of stock. As the coil builds up in size, this manipulation of the coil becomes increasingly difficult. Some rather involved mechanical devices have been made to perform this work.

One of the objects of the present invention is to provide an apparatus for making serpentine coils of a simplified nature wherein a minimum of manipulating movements of the stock is required during the bending operations. To this end, the invention aims to provide an apparatus wherein two reverse bends are simultaneously made and wherein the formed portions of the coil remain substantially at rest during the bending operations with the stock moving substantially only lengthwise in order to provide the necessary length of tube required to form the runs and bends of the coil.

Other objects will become apparent as the following detailed description is considered in conjunction with the accompanying drawings wherein one apparatus for carrying out the invention is disclosed:

Fig. 1 is a general side elevational view of an apparatus constructed in accordance with the invention showing several positions of an operating part in dotted lines.

Fig. 2 is a top plan view showing the support or table and some of the operating parts.

Fig. 3 is a sectional view taken substantially on line 3—3 of Fig. 1 showing a clamp and bending arbor.

Fig. 4 is a sectional view taken substantially on line 4—4 of Fig. 1 showing the yieldable mounting of a bending arbor.

Fig. 5 is a small diagrammatic view illustrating the arrangement of the apparatus.

Fig. 6 is a view illustrating a modified form of arbor.

Fig. 7 is an end view of the modified form of arbor.

2
The apparatus advantageously comprises a suitable support or table having a top portion 1 and supporting legs 2, while other work supporting elements, as indicated at 3, may project from the table any requisite length for carrying the elongated stock, such as the tube, illustrated at 4.

Mounted on the support is a post or anchoring member 7. Adjacent the post 7, and positioned above the same is a cam element 8 provided with an inclined or cammed surface 9 while an adjustable stop 10 is also located on the table adjacent the post 7. A fixed arbor 12 is mounted on the support in a position spaced from the post 7 distances in two directions depending upon the size of coil made. A supplemental support 13 is provided and it may be adjacent the arbor 12 as shown.

Mounted on the table is a swinging arm 15, and this arm is mounted to swing about a pivot on an axis fixed relative to the arbor 12. The pivotal mounting for the arm 15 is illustrated at 16, the same being in the form of a stub shaft in a bearing 17. This shaft extends through the bearing, and on its end opposite the arm 15, is a counterweighted arm 18 for balancing purposes. In the normal rest position, the arm 15 may be supported by an adjustable stop 20. In a simple mechanism the arm 15 may be manipulated by hand and for this purpose it is provided with a handle 21 connected thereto by an arm 22.

The arm 15 carries a bending arbor 25, and this arbor is slidably mounted in the arm. To this end, there is a slide block 26 slidably mounted in an aperture 27 in the arm for which purpose the block comprises a plate portion 26a attached to the portion 26, as by screws 28 so that the two portions overlap opposite sides of the arm and the block is thus retained in position. As shown in Fig. 4, the arbor 25 has a stud 31 which extends through the block 26—26a and is provided on its opposite end with a roller 32. The stud 31 also holds a plate 30 in pivotally mounted position on the block.

A spring structure, which may embody one or more coil springs 35, has one end mounted in a recess 36 in the arm while its other end acts upon the block 26 to urge it to the right as Figs. 1 and 4 are viewed, normally against an adjustable stop 37.

The plate 30 carries a clamp structure for clamping the stock. This clamp structure, as shown in Figs. 1 and 3, includes a fixed clamping block 40 positioned immediately adjacent the arbor 25, but in advance thereof, and a movable clamping block 41 slidably mounted in a guide

42 and which is arranged to be acted upon by a cam or eccentric 43 provided with an operating handle 44.

The apparatus may be employed to bend a single piece of stock or it may be used to bend a plurality of pieces of stock fed to the machine simultaneously. As illustrated in Figs. 2 and 3, two pieces of stock in the form of tube are disposed in the machine. There is a tall piece 47 in the form of a long rod or bar which is attached to the plate 26 and it extends from the machine in the direction from which the stock is supplied and is guided by devices, such as rollers 48 and 49, in the support 3. As shown in Fig. 5, the support 3 is removed quite a distance from the work table. This bar, as will presently be seen, maintains the position of the plate 26 and takes the load off the stock during the swinging action of the arm 15.

The arbors 12, and 25 are shown with smooth surfaces. However, grooved arbors may be used as shown in Figs. 6 and 7. The modified arbor 50 is shown for use with two pieces of stock, and is fashioned with a groove 51 and a groove 52. The side portions of the grooves are cut away at one or more points thus providing flats 53. The flattened off portion does not extend inwardly beyond the bottom of the grooves but merely removes the side portions thereof and this permits removal of the formed tube as will presently be seen.

In the operation of the machine, the several parts are normally in the full-line position shown in Fig. 1. At this time, the stock T may be advanced into the machine. It is threaded between the clamp elements 40 and 41, passed over the arbor 25, under the arbor 12, and beyond the post 7. To make the first bend at y, around the post 7, the operator may merely bend the stock around the post by hand and may then place the end of the stock over the supplementary support 13 so that the stock is now held securely in position. The post 7 is of a size as to provide a bend which may be identical to bends formed by the mandrels. Making sure that the bend y is snug against the post 7, the stock is now clamped by manipulation of the cam 43. With the stock thus located and clamped in the machine, the handle is grasped and the arm 15 is swung on its pivot 16 in a counter-clockwise direction as Fig. 1 is viewed.

The resultant action is that of making two bends simultaneously. As the arm 15 is so rocked on its axis the stock is bent around the arbor 12 as indicated. Also the stock is bent around the arbor 25 as indicated. Inasmuch as the stock is clamped in position so that there is no lengthwise movement or feeding action of the stock during the bending operation, the length of the stock between the center of the arbor 12 and the center of the arbor 25 must be such as to accommodate the length of stock required in two bends and two runs. By that we mean two of the bends y in the serpentine form with two adjacent runs x (Fig. 1).

The operation of forming a bend around the arbor 12 is easily understood as the stock is merely wrapped around the same. As the arm 15 is swung on its axis, any fixed part of the arm swings on a true radius about the axis of the pivotal mounting 16. The curve z represents this function; the curve z is an arc around the pivot 16 on the radius of the center of the arbor 25 when the arm 15 and arbor 25 are in the rest or starting position shown in Fig. 1. How-

ever, as the swinging progresses through the dotted line positions shown, the position of the arbor 25 and clamp must change due to the fact that some of the lineal extent of the tube between the arbor 12 and the clamp 40-41 is taken up in the bends. Accordingly, as the bending operation progresses, the block 26 is shifted in the slot 21 against the action of the spring 35 as some of the stock is taken up in the wrapping action. Accordingly, the arbor 25 and the clamp describe a form of involute curve z'. This may be a compound involute curve generated by wrapping the stock about the two arbors 12 and 25. The action keeps the stock taut. The plate 30 rocks on the axis or stud 31 of the arbor 25 in this action with the result that the clamp stays in line with the length of the stock which is clamped thereby.

As the arm 15 reaches the extreme position as shown to the left, as Fig. 1 is viewed, the two bends around the arbor 12 and the arbor 25 are completed and it is now necessary to remove the bends from the arbors. This is accomplished by pushing the arm in a downward direction at which time the roller 32 engages the inclined surface 8. This pushes the block 26 relative to the arm 15 against the action of the spring 35 toward the arbor 12 to thereby shorten the center to center distance between the arbors so that the two bends may be slipped off the arbors. This is the purpose for providing the flats 53 on the modified arbor structures, shown in Figs. 5 and 6. The clamp is now released, the bends slipped off the arbors, and the coil dropped downwardly so that the bend, which has just been formed about the arbor 25, may be placed over the post 7 and the run of tube immediately under the post hooked over the supplemental support 13. The arm is now swung clockwise to the full line position shown in Fig. 1, the stock again placed between the clamps, under the arbor 12 and over the arbor 25 and after the clamp has been applied the arm is swung counter-clockwise again to make two more bends. This completes one full cycle, and it will be seen how the formed serpentine coil grows downwardly, as indicated by the dotted lines shown in Fig. 1.

As will be appreciated by considering Fig. 1, the long length of stock is elevated from its support and has imparted thereto a swinging action as the arm 15 is oscillated. In this action, the plate 30 and the clamp oscillate about the axis of the stud 31 and some forces must be overcome. This is the purpose of the bar or rod 47 which is attached to the plate 30. This bar, as shown in Fig. 5, is of considerable length and the stock and bar move together in this action. The bar takes whatever load there is in connection with the swinging of the plate 30 and the clamp, thus relieving the long length of stock of these forces.

The post 7, as will be appreciated, performs no bending function in the operation of the machine other than the first bend which is manually made as above described, but is used as a convenient anchor. In other words, the stock must be anchored on the down stream side of the arbor 12 and since, after the first operation, a bend is available for anchoring purposes, such bend is merely placed over the post 7 with the immediate underlying run disposed on the supplemental support 13. This anchors the tube and prevents movement of the tube under the action of the spring 35. The center to center distance between the arbor 12 and the arbor 25, as above

mentioned, is progressively diminished during the bending operation as determined by the take-up in the stock incident to the stock being wrapped about the arbors. To provide a nicety of action, the axis of the pivotal mounting 16 must be so located that all portions of the involute curve z' lies within the arcuate curve z , except in the full-line position shown in Fig. 1 where the two curves may intersect. One factor in the location of the axis of the mounting 16 is the radius of the bends formed. Inasmuch as the stock is supplied to the apparatus, from the right hand side as Fig. 1 is viewed, the anchoring post 1 may be considered as being downstream from the fixed arbor 12 and the clamp 40-41 may be considered applicable to the stock upstream from the arbor 25. Such terminology is used in the claims appended hereto.

I claim:

1. An apparatus for shaping stock of elongated form, such as tube, into coils of serpentine form having a succession of reverse bends, comprising a fixed arbor, a movable member mounted to move about the fixed arbor, a yieldably mounted arbor on said member, means for anchoring the stock on one side of the fixed arbor, a clamp on said member for clamping the stock on the side of the yieldably mounted arbor opposite the fixed arbor, said clamp being yieldably mounted for yieldable shift in unison with the yieldably mounted arbor, and means for moving said member about the fixed arbor to bend the stock around the said two arbors with the arbor on the said member and the clamp shifting yieldably on the member to accommodate the take-up in the stock incident to the wrapping of the stock around the arbors.

2. An apparatus for shaping stock of elongated form, such as tube, into coils of serpentine form having a succession of reverse bends, comprising a fixed arbor, a swinging member, a pivot for the swinging member, an arbor on the swinging member, a clamp on the swinging member, means yieldably mounting the second mentioned arbor and the clamp on the swinging member, means for anchoring the stock on one side of the fixed arbor, said clamp being applicable to the stock on the side of the second mentioned arbor which is opposite that of the fixed arbor, and means for swinging the member on its pivot to bend the stock about both the said arbors.

3. An apparatus for shaping stock of elongated form, such as tube, into coils of serpentine form having a succession of reverse bends, comprising a fixed arbor, a swinging member, a pivot for the swinging member, an arbor on the swinging member, a clamp on the swinging member, means yieldably mounting the second mentioned arbor and the clamp on the swinging member, means for anchoring the stock on one side of the fixed arbor, said clamp being applicable to the stock on the side of the second mentioned arbor which is opposite that of the fixed arbor, and means for swinging the member on its pivot to bend the stock about both the said arbors, the pivot for said swinging member being so located relative to the axis of the fixed arbor that the take-up in the stock, as it is formed about the arbors, shifts the yieldable arbor and clamp on said swinging member.

4. An apparatus for shaping stock of elongated form, such as tube, two coils of serpentine form having a succession of reverse bends, comprising a fixed arbor, a swinging member, a pivot for the swinging member, an arbor on the swing-

ing member, a clamp on the swinging member, means yieldably mounting the second mentioned arbor and the clamp on the swinging member, means for anchoring the stock on one side of the fixed arbor, said clamp being applicable to the stock on the side of the second mentioned arbor which is opposite that of the fixed arbor, and means for swinging the member on its pivot to bend the stock about both the said arbors, the pivot for said swinging member being so located relative to the axis of the fixed arbor that the take-up in the stock, as it is formed about the arbors, shifts the yieldable arbor and clamp on said swinging member in a form of involute curve, all portions of which lie within a true arc described by a point on said member which is concentric with the center of the yieldably mounted arbor before movement of the said member.

5. An apparatus for shaping stock of elongated form, such as tube, into coils of serpentine form having a succession of reverse bends, comprising a fixed arbor, an arm pivotally mounted on an axis adjacent the arbor, a support slidably and rockably carried by the arm, yieldable means acting upon the support, an arbor carried by said support, a clamp carried by said support, said arbors adapted to have a substantially straight run of stock positioned adjacent and substantially tangent thereto, means for anchoring the stock on one side of the fixed arbor, the clamp being applicable to the stock adjacent the arbor on said support and on the side thereof opposite from the fixed arbor, means for swinging said arm about its pivot to cause the stock to be bent about both of said arbors, said yieldable means affording movement of the support on said arm to accommodate for the take up of stock as the same is wrapped around the arbors, said support rockable on its mounting whereby the clamp remains in substantial alignment with the stock held thereby.

6. An apparatus for shaping stock of elongated form, such as tube, into coils of serpentine form having a succession of reverse bends, comprising a fixed arbor, an arm pivotally mounted on an axis adjacent the arbor, a support slidably carried by the arm, yieldable means acting upon the support, an arbor carried by said support, a clamp carried by said support, said arbors adapted to have a substantially straight run of stock positioned adjacent and substantially tangent thereto, means for anchoring the stock on one side of the fixed arbor, the clamp being applicable to the stock adjacent the arbor on said support and on the side thereof opposite from the fixed arbor, means for swinging said arm about its pivot to cause the stock to be bent about both of said arbors, said yieldable means affording movement of the support on said arm to accommodate for the take up of stock as the same is wrapped around the arbors, said clamp being rockable whereby the clamp remains in substantial alignment with the stock held thereby.

65 7. An apparatus for shaping stock of elongated form, such as tube, into coils of serpentine form having a succession of reverse bends, comprising a fixed arbor, an arm pivotally mounted on an axis adjacent the arbor, a support slidably carried by the arm, yieldable means acting upon the support, an arbor carried by said support, a clamp carried by said support, said arbors adapted to have a substantially straight run of stock positioned adjacent and substantially tangent thereto, means for anchoring the stock on

one side of the fixed arbor, the clamp being applicable to the stock adjacent the arbor on said support and on the side thereof opposite from the fixed arbor, means for swinging said arm about its pivot to cause the stock to be bent about both of said arbors, said yieldable means affording movement of the support on said arm to accommodate for the take up of stock as the same is wrapped around the arbors, said clamp being rockable whereby the clamp remains in substantial alignment with the stock held thereby, the pivotal mounting of said arm being so disposed relative to the fixed arbor that the take up in the tube causes the arbor on the arm to describe a form of involute curve substantially all portions of which are within a true arc described on the radius of the arbor on the arm prior to the swinging movement of the arm.

8. An apparatus for shaping stock of elongated form, such as tube, into coils of serpentine form having a succession of reverse bends, comprising a fixed arbor, an arm, means pivotally mounting the arm adjacent the fixed arbor, an arbor on the arm, a clamp on the arm, means yieldably mounting the arbor and clamp for shift of the same relative to the arm, said arbors arranged so that a substantially straight piece of stock may be placed adjacent the same, means for anchoring the stock downstream from the fixed arbor, the clamp being applicable to the stock upstream from the yieldable arbor, means for swinging the arm about its pivot to cause the stock to be wrapped about the two arbors with the yieldable means providing for shift of the arbor on the arm to accommodate for the take up of the stock as the same is wrapped around the arbors, and means active upon the arbor on the arm substantially at the end of the swinging movement to shift the same toward the fixed arbor to thereby loosen the arbors in the bends for removal of the bent portions therefrom.

9. An apparatus for shaping stock of elongated form, such as tube, into coils of serpentine form having a succession of reverse bends, comprising a fixed arbor, an arm, means pivotally mounting the arm adjacent the fixed arbor, a stop upon which the arm may rest, a support slidably and rotatably mounted on the arm, yieldable means for yieldably resisting sliding movement of the support, an arbor carried by the support, a clamp carried by the support, the two arbors being so related that a substantially straight length of stock may be positioned adjacent the same with the arbors on opposite sides thereof, means for anchoring the stock downstream from the fixed arbor, the clamp being applicable to the stock upstream from the arbor on the arm, means for swinging the arm to cause the stock to be bent about the two arbors with the support shifting against the yieldable means to accommodate for the take up of stock as it is bent about the arbors, and means active upon the support substantially at the end of the swinging movement of the arm to shift the support on the arm relative to the fixed arbor to thereby loosen the formed bends on the arbors so that the same may be removed therefrom.

10. An apparatus for shaping stock of elongated form, such as tube, into coils of serpentine form having a succession of reverse bends, comprising a fixed arbor, an arm, means pivotally mounting the arm adjacent the fixed arbor, a stop upon which the arm may rest, a support slidably and rotatably mounted on the arm, yieldable means for yieldably resisting sliding movement of the support, an arbor carried by the support, a clamp carried by the support, the two arbors being so related that a substantially straight length of stock may be positioned adjacent the same with the arbors on opposite sides thereof, means for anchoring the stock downstream from the fixed arbor, the clamp being applicable to the stock upstream from the arbor on the arm, means for swinging the arm to cause the stock to be bent about the two arbors with the support shifting against the yieldable means to accommodate for the take up of stock as it is bent about the arbors, a projection on the support, and an inclined surface engageable by the projection substantially at the end of the swinging movement of the arm to shift the support on the arm toward the fixed arbor to thereby loosen the formed bends on the arbors for removal of the same therefrom.

11. An apparatus for shaping stock of elongated form, such as tube, into coils of serpentine form having a succession of reverse bends, comprising a fixed arbor, a pivotally mounted arm having its pivot adjacent the fixed arbor, an arbor and clamp unit slidably mounted on the arm, yieldable means acting upon the unit, a stop for determining the rest position of the arm, said arbors being so related that a substantially straight piece of stock may be positioned adjacent the arbors with the arbors on opposite sides of the stock, means for anchoring the stock downstream from the fixed arbor, said clamp being applicable to the stock upstream from the arbor on the arm, means for swinging the arm about its pivot to bend the stock about both arbors, the yielding means serving for movement of the arbor and clamp unit on the arm to accommodate the take up of stock as the same is formed about the arbors, whereby said unit moves in a path having a form of an involute curve, and means for shifting the arbor and clamp unit substantially at the end of the movement of the arm for loosening the bends on the arbors whereby the same may be removed therefrom.
